MACHINES FOR ATTACHING STRIP MATERIAL TO INSOLES

Milton H. Roske, Boxford, Mass., assignor to United Shoe Machinery Corporation, Flemington, N.J., a corporation of New Jersey

Filed July 2, 1959, Ser. No. 824,585
28 Claims. (Cl. 12—20)

This invention relates to machines for attaching strip material to work pieces, and more particularly to a machine for adhesively attaching ribbed strips to insoles to prepare the insoles for use in the manufacture of welt shoes. The invention is herein illustrated as embodied in a machine of the type disclosed in United States Letters Patent No. 2,670,480, granted March 2, 1954, upon an application filed in the name of A. S. Clark, as modified and improved in accordance with Letters Patent of the United States No. 2,979,744, granted April 18, 1961, upon an application, also filed in the name of A. S. Clark. It is to be understood, however, that in certain of its aspects the invention is not limited to machines of that type.

It is a general object of the present invention further to improve the machine of the patent and the above-named application in order to render it more efficient in operation and capable of producing more uniform results.

For the attainment of this general object, there is provided in the herein illustrated machine, in combination, a support for an insole, a member operated intermittently to press successive portions of a ribbed strip to the margin of the insole and to feed the insole and the attached strip at a variably predetermined rate, power operated means for imparting pressing and feeding movements to said member, means operatively connected to said member and actuated thereby in timed relation to its feeding movement to feed the strip toward engagement with the insole, means including a member over which the strip is guided in its movement toward the point of application for dispensing adhesive to coat the attaching flanges of the strip near the point of convergence between the strip and the insole, means also operatively connected to said pressing and feeding member and actuated thereby in timed relation to its feeding movement to feed adhesive from a source of supply to the dispensing means, margin control means including an edge gage against which the edge face of the insole is maintained by the operator to guide the insole during a strip attaching operation, means operatively connected to the pressing and feeding member and actuated in timed relation to the feeding movement thereof to move the edge gage on the insole support to shift the insole at certain times laterally with relation to the pressing and feeding member so as to vary the distance from the insole edge at which the strip will be attached along different portions of the insole, means for severing the strip after attachment, means actuated by the edge gage shifting means to stop the operation of the pressing and feeding member when the attaching operation reaches a predetermined point along the periphery of the insole, and means actuated by the means for stopping the operation of said member to operate the severing means.

As more particularly illustrated herein, the pressing and feeding member comprises a unitary foot having an inverted T-shaped slot for receiving the ribbed portion of the strip and portions at the opposite sides of the slot acting on the outer and inner flanges of the strip to press them against the insole and to feed the insole after each successive attaching operation. The foot is operated through a closed orbital path by a pair of eccentrics on the main shaft of the machine, of which one eccentric

2

imparts to the foot, through appropriate connections, intermittent vertical components of movement to press the flanges of the strip, while the other eccentric, also through suitable connections, imparts to the foot intermittent horizontal components of movement to feed the work.

The strip to be attached to an insole is drawn from a source of supply and is passed through guide means forming part of a strip feeding assembly comprising a pair of rolls which engage the strip at the opposite sides of the rib portion and are rotated in opposite directions to feed the strip in engagement with a member which is located close to the presser foot and through which adhesive is extruded during an attaching cycle of the machine to coat the flange portions of the strip just in advance of the point of convergence between the strip and the insole. The strip feeding rolls are driven by a shaft which, through connections to a bar to which the presser foot is attached, is rotated intermittently as the bar is reciprocated in a horizontal plane by the previously mentioned eccentric which imparts to the presser foot its horizontal components of feeding movement.

The adhesive, in the form of a solid but flexible rod of thermoplastic cement, is fed from a source of supply by a pair of wheels driven by a shaft which, through suitable connections to the previously mentioned presser foot bar, is rotated intermittently as the bar is reciprocated in a horizontal plane, as above noted, to impart to the presser foot horizontal components of feeding movement. The cement rod is fed into a heated casing forming a part of a melting and dispensing device in which the cement is melted to render it viscous and from which the molten cement is pumped by a gear pump, also driven by the shaft which drives the feed wheels, to supply heated liquid cement to the previously mentioned member from which it is extruded to coat the flange portions of the strip as the latter is moved over the member by the strip feeding rolls toward engagement with the insole. The flow of cement into the just mentioned member is controlled by a valve which is opened by means rendered operative by depression of an operating treadle to start an attaching operation and closed when the treadle is released. To insure an adequate supply of cement for coating the leading end of a strip to be attached to an insole, there is provided, in accordance with a feature of the invention, means actuated by initial depression of the operating treadle to rotate the shaft which drives the cement feeding wheels so as to start feeding cement into the melting and dispensing device before full depression of the treadle renders the eccentric which imparts feeding movement to the presser foot operative to rotate the shaft intermittently.

While the machine is inoperative the strip feeding assembly referred to above is maintained in a raised position spaced from the member over which the strip is fed by the feed rolls and which is heated to maintain the adhesive supplied to it in liquid state, in order to prevent the adhesive by which the plies of material which form the ribbed portion of the strip are bonded from being softened by contact of the strip with the heated extrusion member. In accordance with another feature of the invention, the means previously mentioned which is rendered operative by initial depression of the treadle to start the feed of cement is also effective to move the strip feeding assembly downward into position to bring the strip into engagement with the extrusion member, the assembly being automatically raised to its initial inoperative position at the conclusion of an attaching operation.

70 The edge gage in the illustrated machine is moved, as earlier stated, to shift the insole at certain times in an attaching cycle by a cam which is rotated intermittently

by a shaft driven through connections to the eccentric on the main shaft which imparts to the presser foot its horizontal components of feeding movement. In accordance with a further feature of the invention, means is provided in the driving connection between the cam shaft and the eccentric for rotating the cam shaft at speeds variably predetermined according to differences in insole sizes, in order to insure that the cam will complete a revolution in the time required by the presser foot to operate around the periphery of an insole from the starting to the finishing point. 10

In accordance with a still further feature of the invention, the cam is provided with a member which, when the cam reaches its starting position after completing a revolution, actuates means which breaks the connection between the operating treadle and the power means which imparts feeding movement to the presser foot, thereby automatically stopping the operation of the foot, the strip feeding means, and the cement feeding means. 15

In accordance with yet another feature of the invention, means is provided which is rendered operative on the breaking of the connection between the operating treadle and the presser foot operating means, as previously indicated, to actuate a knife to sever the strip. At the end of its operative stroke the knife actuates means which permits the treadle to be reconnected to the presser foot operating means for starting a subsequent operation of the machine. 20

These and other features of the invention will be more clearly understood from the following description, in conjunction with the accompanying drawings, and particularly pointed out in the claims. 30

In the drawings,

FIG. 1 is a front elevation of the head of an illustrative machine embodying the invention;

FIG. 2 is a side elevation of the base of the machine;

FIG. 3 is a sectional plan view, taken along the line III-III of FIG. 2, of means for adjusting the heightwise position of the work support;

FIG. 4 is a side elevation of the machine;

FIG. 5 is a perspective view of the principal operating mechanisms of the machine for feeding and attaching a strip to an insole, feeding the insole and attached strip, and guiding the insole during a strip attaching operation;

FIG. 6 is a perspective view of a heel gage mechanism for initially locating an insole on the work support with relation to a strip attaching and work feeding presser foot;

FIG. 7 is a perspective view of holdown means operated to hold the insole against the work support when the presser foot is moved out of engagement with the insole;

FIG. 8 is a view in right-hand side elevation of a portion of the driving mechanism of the machine for operating the presser foot;

FIG. 9 is a detail rear view of means operated by the mechanism shown in the lower right-hand portion of FIG. 1 for automatically stopping the operation of the presser foot;

FIG. 10 is a view in front elevation and on an enlarged scale of mechanism shown in the lower left-hand portion of FIG. 1 for feeding a strip toward an insole and of part of a mechanism for extruding thermoplastic cement to coat the strip before it engages the insole;

FIG. 11 is a right side elevation on an enlarged scale of a portion of the strip feeding mechanism shown in FIG. 10;

FIG. 12 is a detail view in rear elevation and at a slight angle of the strip feeding mechanism shown in FIG. 11;

FIG. 13 is a bottom view of the strip feeding mechanism shown in FIGS. 11 and 12;

FIG. 14 is a detail plan view of a portion of a nozzle and of means for operating a valve forming part of the cement dispensing mechanism;

FIG. 15 is a detail view in front elevation of the nozzle and the valve, which is shown in the open position;

FIG. 16 is a view similar to FIG. 15, with the valve shown in closed position;

FIG. 17 is a detail view in right side elevation of a work supporting table and of the strip feeding and coating means;

FIG. 18 is a perspective rear view of driving means for the cement dispensing mechanism;

FIG. 19 is a detail plan view on an enlarged scale of an edge gage and cam mechanism for operating the gage to shift the insole laterally of the work support during a strip attaching operation;

FIG. 20 is a front elevation of the mechanism shown in FIG. 19;

FIG. 21 is a detail plan view of the mechanism shown in the left-hand portion of FIG. 20;

FIG. 22 is a detail view in left side elevation of the edge gage and associated parts;

FIG. 23 is a left side elevation of mechanism shown in the upper left-hand portion of FIG. 1 for initially determining the speed of rotation of the edge gage operating cam in accordance with insole sizes;

FIG. 24 is a plan view of the edge gage operating cam;

FIG. 25 is a diagrammatic view showing an insole in its relation to the strip feeding and attaching mechanism and the cement feeding and dispensing mechanism;

FIG. 26 is a detail of a portion of the mechanism shown in FIG. 25;

FIG. 27 is a perspective view of an insole with a ribbed strip attached thereto in the machine;

FIG. 28 is a wiring diagram; and

FIG. 29 is a schematic view showing the various electrical controls and the related mechanisms operated thereby.

Work Support

The machine comprises a base or column 50 (FIGS. 1, 2 and 4) having at its upper end a plate 52 to which is bolted a casting or head 54 which supports the various operating instrumentalities of the machine. In the casting 54 there is provided a dovetail guideway 56 in which is mounted for heightwise movement a slide 58 having affixed thereto by a screw 60 (FIG. 1) a work support comprising a table 62 and a roll 64 rotatably mounted on a stud 66 fixed in the upper portion of the table. For lowering the table to facilitate the insertion of an insole there is pivoted on the slide 58 by a stud 68 the upper end of a link 70, the lower bifurcated end of which is pivotally connected by a pin 72 to one arm of a bell crank lever 74 fulcrumed on a stud 76 extending through a block 78 slidably mounted in the guideway 56. The other arm of the lever 74 is connected by a rod 80 to a treadle 82 fulcrumed on a shaft 83 mounted in the base of the machine. The link 70 and the bell crank lever 74 form a toggle which, in its straightened position, holds the table elevated but is broken when the treadle 82 is depressed to lower the table. A spring 84 attached at one end to the treadle and at its other end to a screw eye 85 threaded into the machine base returns the table to its normal position when the treadle is released. An abutment 86 fastened to the machine base limits the reverse movement of the toggle 70, 74 to its straightened position.

The heightwise position of the table may be adjusted 65 with relation to a presser and feed foot 100 (FIGS. 4, 5 and 7) which extends in a direction normal to the work engaging surface of the roll 64, and which is operated, by mechanism to be described, to press a ribbed strip against an insole supported by the roll 64 and, in cooperation with this roll, to feed the insole and the strip attached thereto. For this purpose there is secured in the guideway 56 a split block 102 (FIGS. 2 and 4) through which is threaded an upwardly extending screw 104 formed at its upper end with a head in the form of 70 a disk 106 received in a horizontal slot 107 provided in

the block 78. At its lower end the screw 104 is provided with a knurled knob or hand wheel 108 the upper face of which, as shown in FIG. 3, has a plurality of markings or graduations 110 each of which represents an insole "iron" or thickness. To adjust the table at the proper height for insoles of a given thickness, the screw 104 is rotated until one of the markings on the wheel 108 registers with a pointer 112 (FIGS. 3 and 4) slidably mounted in a bracket 114 fixed to the block 102. When the screw is rotated in one direction or the other the disk 106, acting through the block 78 on the toggle formed by the bell crank lever 74 and the link 76, raises or lowers the slide 58 and with it the table 62.

Heel Gage

The insole to which a ribbed strip is to be attached is introduced into the machine between the roll 64 and the presser foot 100 with its heel end pointing rearwardly of the machine or away from the operator. The attachment of the strip usually commences at the heel breast line at one side of the insole and, after rounding the toe end, terminates at the heel breast line at the opposite side. For locating the insole in the position in which the heel breast line will be in register with the presser foot for commencing an attaching operation at the desired point, there is provided a heel gage 116 (FIGS. 4 and 6) located rearwardly of the presser foot and comprising a sleeve 118 mounted for sliding movement rearwardly or forwardly of the machine in a guideway formed in a block 120 extending transversely of the machine. The sleeve 118 surrounds a screw 122 extending through a block 124 and having collars 126, 128 fixed to it at opposite sides of the block 124. By turning the screw 122 in one direction or the other the sleeve 118 may be moved forwardly or rearwardly to adjust the heel gage 116 in the desired position to locate the insole to be operated upon relatively to the presser foot 100 in the position to determine the starting point of the strip attaching operation. To the block 120 is secured an upwardly extending arm or slide 130, in the shape of an inverted L and slidable in a guideway formed in a bracket 132 secured to the machine head. The under surface of the horizontal arm of the slide 130 is cam shaped and is engaged by a roll 134 mounted on a screw 136 threaded into one end of a horizontal rod 138, the other end of which is fastened in a block 140 secured to a lever 142 pivoted at 144 (FIG. 8) on the machine head 54. To the lever 142 is connected the upper section 146 of a two-part rod, the lower section 147 of which is connected to a treadle 148 (FIG. 2) pivoted on the shaft 83. Depression of the treadle 148 causes the lever 142 to turn in a clockwise direction to render operative power operated means, to be described later, to start operation of the presser foot 100. By this movement of the lever 142 the rod 138 (FIG. 6) is moved in the same direction, whereby the action of the roll 134 on the cam surface of the horizontal arm of the slide 130 causes the slide to move upwardly to lift the heel gage 116 out of engagement with the insole at the beginning of an attaching operation.

Strip Feeding Means

The strip S which is to be attached to an insole is drawn from a reel 150 (FIG. 25) supported on a bracket 152 secured to the machine head and is guided first around a pulley 154 (FIG. 4) mounted on a bracket 155 bolted to the head, then over a wedge-shaped plow or spreader 156 (FIGS. 10 and 15) which engages between the strip flanges and causes them to be spread outwardly or substantially at right angles to the rib portion. The spreader 156 is formed on a horizontal arm 158 of a bracket 160 secured by screws 162 to a casting or block 164 which carries strip feeding devices to be described, and therefore sometimes referred to hereinafter as the strip feeding assembly. For a purpose to be explained hereinafter, the casting 164 is mounted for movement heightwise of the machine on a bracket 166 secured by a screw 167 to the

bracket 155 and having a T-shaped rib 168 (FIG. 14) engaging in a similarly shaped groove formed in the left-hand edge face of the casting. After the spreader 156 has spread apart the flanges of the strip, the strip is passed through a rib receiving slot 169 formed in a first or outer guide member 170 (FIG. 15) secured to the bracket 160, and then along a downwardly and rearwardly (or inwardly) inclined surface of a heated block 172 which, as will appear hereinafter, also serves as a nozzle through which adhesive is extruded to coat the flanges of the strip just prior to operation of the presser foot on the successive portions of the strip to bond them to the insole. The strip is fed along the surface of the block 172 and through a vertical slot 173 (FIG. 12) provided in a second or inner guide member 174 formed integral with the block or casting 164, by a pair of toothed rolls 176, 178 (FIGS. 10, 11, 12 and 13) engaging the opposite sides of the rib portion of the strip. The rolls 176, 178 are mounted, respectively, on pins or shafts 180, 182. The shaft 180 which carries the feed roll 176 is rotatably mounted in spaced horizontal arms 184 of a lever 186 pivoted on a pin 188 set in the casting 164. A screw 190 threaded through the lever 186 and into the casting 164 is surrounded by a spring 192 by which the roll 176 is biased toward the roll 178 and against the resistance of which the lever may be swung counterclockwise (as seen in FIG. 10) about the pin 188 to separate the roll 176 from the roll 178 to permit passing the rib portion of the strip between them when the leading end of the strip is initially threaded into the machine. The shaft 182 is rotatably mounted in the casting 164 and carries on its upper end a gear wheel 194 meshing with a similar gear wheel 196 fast on the upper end of the shaft 180. The gear wheel 194 also meshes with a gear wheel 198 fast on a shaft 200 connected through a universal coupling 201 to the lower end of a vertical shaft 202 (FIGS. 1, 5 and 10) the upper end of which is connected through a universal coupling 203 to a shaft 204 (FIG. 23) journaled in a bearing sleeve 205 joined by a web 206 (FIG. 1) to a bearing sleeve 208 formed integral with a bracket 210 fixed by bolts 212 to the machine head. Within the sleeve 208 is journaled one end of a horizontal shaft 214 the other end of which is journaled in a bracket 216 fixed to the machine head.

The feed rolls 176, 178 are rotated by the shaft 202 to feed the ribbed strip through mechanism comprising a bevel gear 218 pinned to the upper end of the shaft 204 and meshing with a bevel gear 220 pinned to the shaft 214. To the shaft 214 is keyed a one-way roller clutch 222, 224. The upper end portion of the clutch member 224 is provided with a slot which is engaged by a pin 226 projecting laterally from the bracket 216. A second one-way roller clutch 228, 230 is keyed to the shaft 214 adjacent to the gear 220, the member 230 of this clutch being pivotally connected by a pin 232 (FIG. 5) to a crank 234 formed integral with a short shaft 236. Under the action of means, shortly to be described, by which the presser foot 100 is operated to attach the strip and feed the work by intermittent steps of variably predetermined length, the crank 234 on the shaft 236 reciprocates the clutch member 230 to rotate the shaft 214 in one direction and, through the above-described driving connections, to rotate the feed rolls 176, 178 so as to advance the strip toward engagement with the insole in timed relation to the intermittent feed of the insole by the presser foot. During the reverse movement of the crank 234, the clutch 222, 224 acts as a brake to hold the shaft 214 against reverse rotation.

Strip Attaching and Work Feeding Means

The means for actuating the presser foot 100 to impart to it intermittent strip attaching and work feeding movements will now be described. Referring to FIGS. 4 and 5, the shaft 236 has secured to it the forward end of a link 238, the rear end of which is pivotally connected by a pin 239 to the upper end of a vertical bar 240 to the lower end of which is attached the presser foot 100. To the bar

240 is pivotally connected by a short shaft or pin 242 the forward or outer end of an arm 244 fulcrumed at its rear or inner end on a pin 246 fastened in a boss 247 formed on the machine head or casting 54. On the pin 246 is also fulcrumed the inner or rear end of an arm or lever 248. Between the arms 244 and 248 is interposed a compression spring 250 seated in alined openings in the arms and surrounding a screw 252 having threaded on its upper end lock nuts 254 by which the tension of the spring may be initially adjusted. The forward or outer end of the arm 248 is pivotally connected by a pin 256 to the lower end of a vertical rod 258, which is pivotally connected at its upper end by a pin or shaft 260 to a horizontally extending strap 262 surrounding an eccentric 264 fast on the main drive shaft 266 which is rotatably supported in bearings in the machine head (FIG. 1). The shaft 266 is provided with a fly wheel 268 and is rotated continuously by a pulley 270 connected by a belt 272 (FIG. 2) to the shaft 274 of an electric motor 276 supported on a bracket 278 fixed to the base 50 of the machine.

Through mechanism more fully described in Patent No. 2,670,480, previously referred to, the eccentric 264 imparts reciprocating vertical movement to the rod 258 which, through the above described connections between this rod and the bar 240, including the arms 248, 244 and the spring 250, reciprocates the bar 240 and the presser foot 100 which is secured to it to press successive portions of the flanges of the ribbed strip against the margin of the insole. The mechanism by which the eccentric 264 thus operates the rod 258 and the bar 240 to reciprocate the presser foot vertically comprises a pair of inverted U-shaped yokes or links 280, 282 (FIGS. 1, 4 and 5). The arms of the inner yoke 280 are secured at their lower ends to the shaft 260, the yoke being mounted at its upper or bridged end for swinging movement relative to the outer yoke 282 on a shaft 284 fastened to the arms of this yoke. The opposite arms of the outer yoke 282 are secured respectively to shaft 286, 288 journaled in the machine head 54. The shaft 288 extends beyond the head 54 and has secured to its outer end a lever 290 (FIGS. 8) carrying at its lower end a roll 292 which is held in engagement with a cam surface 294 on the lever 142 by a spring 296 attached at one end to the lever 290 and at its other end to a pin 298 in the machine head. The yokes or links 280, 282 and the rod 258 form between them what, for convenience, may be termed a toggle arrangement of which the shaft 284 is the movable pivot. While the links and the rod are in vertical alinement with one another, the action of the eccentric 264, which is rotated continuously by the shaft 266, is without effect on the presser foot, which will be merely oscillated without exerting any pressure on the work. However, when the starting treadle 148 is depressed to operate the machine, downward movement of the treadle rod 146 swings the lever 142 in a clockwise direction, as seen in FIG. 8, about its fulcrum 144 and the lever 290 is swung in a counterclockwise direction, against the tension of the spring 296, thereby turning the shaft 288 in the same direction. The yokes 280, 282 are thereby swung out of alinement with the rod 258, that is, to a position in which the toggle formed by the yokes and the rod 258 is broken and the shaft 284 is moved closer to the shaft 242 connecting the presser foot bar 240 to the arm 248, so that rotation of the eccentric 264 will alternately make and break the toggle and operate the rod 258 to impart reciprocating vertical movements to the bar 240 to cause the presser foot 100 to press the strip against the insole. Upon continued depression of the treadle 148, the roll 292 carried by the lever 290 engages a second cam surface 300 on the lever 142, which surface is concentric with the center of the fulcrum 144 about which the lever 142 turns, thereby maintaining the toggle in the broken position until the treadle is released.

As more fully explained in the previously cited Patent No. 2,670,480, the presser foot 100 is moved in a counter-

clockwise direction through a substantially elliptical path normal to the plane of the insole, with combined vertical and horizontal components of movement to press the strip and feed the insole and the attached strip. The mechanism by which the presser foot bar 240 is operated to impart to the presser foot its horizontal component of feeding movement is substantially similar to that above described for reciprocating the bar vertically to impart pressing movement to the presser foot. Referring more particularly to FIGS. 4 and 8, a second eccentric 302 on the main shaft 266 is surrounded by a downwardly extending strap 304, which is pivotally connected at its lower end by a shaft 306 to the rear end of a horizontal rod 308, the forward end of which is pivotally connected by a stud or shaft 310 to the upper end portion of the presser foot bar 240. On the outer end of the shaft 306, which extends beyond the strap 304 and the rod 308, is secured a U-shaped yoke or link 312 similar to the inner yoke 280 referred to above. The yoke 312 is surrounded by an outer U-shaped yoke or link 314 in the arms of which is mounted a shaft 316 about which the inner yoke 312 pivots in the same manner in which the inner yoke 280 pivots about the shaft 284 mounted in the outer yoke 282 previously described. One arm of the outer yoke 314 is secured to a horizontal shaft 318 (FIG. 8) journaled in the machine head and extending beyond it. The opposite arm of the same yoke is secured to a similar shaft, not shown, also journaled in the machine head. On the outer end of the shaft 318 is secured a lever 320 normally held in a horizontal position against a stop 322 by a spring 324 attached at one end to the lever and at its opposite end to a pin 326 in the machine head.

The lever 320 carries a roll 328 which, when the lever 142 is turned in a clockwise direction by downward movement of the treadle rod 146, engages a cam surface 330 on the lever 142, which causes the lever 320 to swing clockwise, as seen in FIG. 8, and rotates the shaft 318 in the same direction, whereby the yokes 312, 314 are moved out of alinement with the rod 308, thus breaking the toggle formed by this rod with the yokes. Thereafter rotation of the eccentric 302 will make and break the toggle and reciprocate the rod 308 in a horizontal plane to impart horizontal movement to the bar 240 to cause the presser foot 100 attached thereto to feed the insole and attached strip intermittently with feed strokes of varying lengths as determined by the angular displacement of the yokes relatively to the rod 308 by depression of the treadle. As in the machine of the previously cited Patent No. 2,670,480, provision is made in the present machine for initially determining the limit of angular movement of the yokes 312, 314 so as to determine the maximum length of the feeding component of movement of the presser foot, thereby to determine the maximum rate of feed of the work. For this purpose there is secured to the feed control lever 142 an abutment member 331 (FIG. 8) having a projecting portion which, as the lever is swung clockwise, is arranged to engage an adjustable stop screw 332 extending downwardly through a bracket 333 secured to the top of the machine head. By adjusting the screw 332 the limit of clockwise movement of the lever 142, and hence that of the lever 320 by which the means just described is actuated to impart feeding movements to the presser foot, may be variably determined to vary the maximum rate of work feed.

As the presser foot bar 240 is reciprocated in the manner above described, the link 238 (FIG. 5) connecting the bar to the crank 234 on the shaft 236 reciprocates the clutch member 230, against the tension of a spring 334 attached at one end to the pin 232 securing the clutch member to the crank 234 and, at its other end, to a bracket 335 secured to the top of the bracket 216 (see FIG. 4). Reciprocation of the clutch member 230 rotates the horizontal shaft 214 intermittently in a direction to rotate, through the gears 220, 218, the vertical shaft 202 to which the gear wheel 198 (FIG. 10) is se-

cured, thereby to rotate the feed rolls 176, 178 to feed the strip in timed relation to the feed of the insole by the presser foot 100. As explained earlier, during reverse rotation of the clutch 228, 230 the clutch 222, 224 acts as a brake to prevent reverse rotation of the shaft 214 and thus prevents back feeding of the strip.

Cement Dispensing and Strip Coating Mechanism

The strip S to be attached to insoles in the present machine is preferably of the type disclosed in United States Letters Patent No. 2,774,699, granted December 18, 1956, upon an application filed in the name of Alfred S. Clark. This strip, as illustrated in FIGS. 26 and 27, is composed of two plies of material bonded together throughout portions of their respective widths to form an upstanding rib portion R and laterally extending attaching flanges F1 and F2 which, for use in the machine of the present invention, are left uncoated in the prefabricated ribbed strip, the flanges being, as indicated earlier, coated with adhesive by the extrusion member 172 as the strip is moved along the inclined surface of this member toward engagement with the insole and just before it is acted upon by the presser foot to attach it to the insole.

The adhesive employed in the present machine to coat the strip flanges is in the form of an elongated solid, but flexible, rod C of thermoplastic cement of the type disclosed, for example, in United States Letters Patent No. 2,874,084, granted February 17, 1959, upon an application filed in the name of Hans C. Paulsen. As illustrated diagrammatically in FIG. 25, the rod of cement C is drawn from a reel 336 supported on a bracket 338 fixed to the machine head. The cement rod is moved into a block 340 (see FIG. 4) having a guide tube 342 (FIG. 25) for receiving the rod, the tube being cut away at its opposite sides to permit the rod to be engaged by a pair of feed wheels 344, 346 by which the cement rod is caused to move through an inlet tube 348 into a casing 350 forming part of a melting and dispensing device substantially of the type disclosed in United States Letters Patent No. 2,765,768, granted October 9, 1956, also upon an application of Hans C. Paulsen. Within the casing 350, which is heated by electrical units 352, there is mounted on a shaft 354 a disk 356 provided around its periphery with a pasageway 358 from which the molten cement is discharged into a chamber 360 from which it is supplied by a pump formed by a pair of gears 362, 364 to an inclined passageway 366 formed in a nozzle housing or carrier 368 (see also FIGS. 1, 4 and 10) secured to the casing 350 and heated by electrical units 370 to maintain the cement in molten condition. The inclined passageway 366 is arranged to communicate with an orifice 372 in a valve 374 housed in the nozzle carrier 368 and having a stem 376 on which is fastened a pinion 378 meshing with a rack bar 380 slidable in a T-shaped slot formed in a block 382 secured to the casing 350. The rack bar 380 is connected by a spring 383 to a link 384 (FIGS. 4 and 18) which is in turn connected by a bell crank lever 386 and a link 387 to the armature 388 of a solenoid 390 supported on a bracket 391 secured to the machine head 54. The solenoid 390 is energized by a normally closed microswitch 392 which is held open by engagement with a roll 394, carried by the switch arm, of a finger 396 pinned on the shaft 286 on which is secured one arm of the yoke 282 and which extends beyond the bracket 216. A spring 398 is secured at one end to a pin 399 on the link 384 and at its other end to a lug 400 depending from the machine head. When, upon depression of the treadle 148 to start an attaching operation, the yoke 282 is swung forwardly of the machine, or clockwise with reference to FIG. 4, and the shaft 286 is rotated in the same direction, the finger 396 is disengaged from the roll 394, whereby the switch 392 is closed to energize the solenoid 390. The rack bar 380 and the link 384 are thereby moved as a unit rearwardly, or to the left of FIG. 4, expanding the spring 398. By this movement of the rack bar the pinion 378 (FIG. 10) is rotated and rotates the valve 374 to the

position in which its orifice 372 is placed in communication with the passageway 366. Heated melted cement is then permitted to flow from this passageway through the orifice 372 into a vertical passage 401 (FIGS. 10 and 16) in the valve and thence through a lateral passage 402 provided in the block or nozzle 172, which passage communicates with a plurality of capillary grooves 403 formed in the block and through which cement is extruded in the form of a plurality of ribbons or threads onto the flanges of the strip as the strip is fed toward the insole. The cement cools and sets almost instantaneously upon contact of the strip flanges with the insole, so that the attaching operation continues without interruption. When the solenoid 390 is deenergized by the opening of the microswitch 392 upon release of the operating treadle 148, the spring 398 returns the rack bar to its initial forward position and, by rotating the pinion 378 in reverse direction, rotates the valve 374 to the position in which its orifice 372 is out of communication with the inclined passageway 366 in the nozzle carrier 368, thereby interrupting the supply of cement to the extrusion nozzle 172. If the operating treadle should be depressed to operate the machine before the solid rod cement has been sufficiently heated to render it flowable, the link 384 connecting the rack bar 380 to the armature of the solenoid 390 will be moved rearwardly, or to the left of FIG. 4, without moving the rack bar, by reason of the yielding connection provided by the spring 383, thereby preventing damage to the parts.

The solid rod cement is fed into the casing 350 of the melting device by mechanism which is operatively connected to the power means described above for operating the presser and feed foot 100, and which is driven in timed relation to the feeding movement of the foot. Referring to FIGS. 4 and 5, a cross link 404 is pivotally connected at its forward end by the shaft 310 to the presser foot bar 240 which, as already explained, is oscillated by the eccentric 302 about the shaft 242 to impart intermittent feeding movements to the foot 100. The rear end of the link 404 is adjustably connected to an arm or lever 406 (see also FIG. 18) by means of a stud 408 engaging in a slot 410 provided in the lever 406. By adjustment of the link 404 into different positions relatively to the lever 406, the rod cement feed increments may be lengthened or shortened to vary the amount of cement extruded through the nozzle 172 in accordance with the individual preferences of operators or with differences in the characteristics of work pieces to be bonded in the machine.

The lever 406 is fulcrumed at its lower end on a pin 412 (FIG. 18) in a bracket 414 secured to the machine head, and has an upwardly extending arm 416 connected to an arm 418 by a pin 420 engaging in a slot 422 in the arm 418. The arm 418 is pinned to a shaft 424 rotatably mounted in a bracket 426 fixed to the machine head. Also pinned to the shaft 424 is a rocker 428 having a forwardly extending arm 430 and a rearwardly extending arm 432. The arms 430, 432 are connected respectively by adjustable links or rods 434, 436 to a pair of Horton-type clutches 438, 440 pinned to a horizontal shaft 442 and rotated in opposite directions through a half revolution to rotate the shaft stepwise. The shaft 442 is journaled in bearing blocks 444, 445 extending rearwardly from the machine casting or head 54, and carries near its outer end a sprocket wheel 446 which is coupled to the shaft to turn therewith through a clutch 447 that is urged into frictional engagement with the sprocket wheel with adjustably variable pressure by means of a spring 448 surrounding the shaft between a collar 449 and a knurled wheel 450 threaded on the outer end of the shaft. The sprocket wheel 446 is engaged by a chain 451 which also meshes with a sprocket wheel 452 keyed to a shaft 453, to which is also fastened the upper feed wheel 344 which cooperates with the lower feed wheel 346 to feed the rod cement C into the casing 350 of the melting device. The sprocket wheel 452 is frictionally coupled to the shaft 453 to turn with it by a clutch 454 which is urged toward the sprocket

with variably adjustable pressure by a compression spring 455 surrounding the shaft between a collar 456 and a knurled wheel 457 threaded on the outer end of the shaft. On the same shaft 453 is pinned a gear 458 meshing with a gear 459 pinned to a shaft 460 (FIG. 4) which carries the lower feed wheel 346. The sprocket chain 451 connects the sprocket wheels 446 and 452 to a sprocket wheel 462 pinned to a shaft 464 to which is also pinned a gear 466 meshing with a gear 468 carried by the shaft 354 on which is mounted the melting disk 356 in the casing 350. The friction clutch means above described for rotating the sprocket wheels 446 and 452 permit these wheels to slip on their respective shafts if the operator should attempt to start operation of the machine before the solid rod cement has been heated to render it flowable, thereby guarding against damage to the parts of the cement dispensing mechanism.

It is desirable that, upon depression of the treadle, a quantity of adhesive be supplied promptly to the extrusion nozzle 172 to insure that the flanges of the leading end of the strip will be suitably coated before the presser foot acts to press the strip against the insole. For this purpose there is pinned to the shaft 442 a Horton-type clutch 470 (FIGS. 8 and 18) to which is secured an upwardly extending arm 472 having a slot 474 through which extends a stud 476 engaging in a slot 478 provided in the lower end portion of a vertical link 480 which is pivoted at 482 on a bracket 484 extending from the machine head 54. The upper end of the link 480 is pivotally connected by a link 486 to the armature 488 of a solenoid 490 which is energized by a microswitch 492 (FIG. 8) held open by engagement of a pin 493 carried by the lever 142 with a roll 494 carried by an arm 496 of the microswitch. The arrangement is such that, when the lever 142 is swung in a clockwise direction by depression of the treadle 148 to start operation of the presser and feed foot, disengagement of the pin 493 from the roll 494 closes the microswitch 492 and energizes the solenoid 490, whereby the link 480 is swung in a clockwise direction (as shown in FIG. 18), or counterclockwise as viewed from the front of the machine about its pivot 482 and, through the clutch 470, rotates the shaft 442 so as to rotate the feed wheels 344, 346 to feed a length of the cement rod into the melting and dispensing device 350 before the power means which actuates the presser foot bar 240 becomes effective to operate the presser foot and the rod cement feeding mechanism. The link 480 swings against the tension of a spring 498 attached at one end to a bracket 500 secured to the link and at its other end to a pin 502 projecting from the machine head 54.

It has been stated previously that the strip to be attached to insoles in the present machine is composed of two plies of material which are coated with adhesive throughout portions of their respective widths to form the rib portion and leaving uncoated portions which constitute the flanges by which the strip is secured to the insole. Since the block or nozzle 172, along which the strip is guided toward the insole and through which cement is extruded to coat the flanges of the strip, is heated in order to maintain the adhesive in molten condition, it is desirable that the casting 164 which carries the strip guiding and feeding means be maintained out of engagement with the heated nozzle 172 while the machine is idle, in order to prevent softening of the adhesive by which the two plies of the rib portion of the strip are bonded together, the casting being lowered into engagement with the nozzle when the starting treadle 148 is depressed to commence an attaching operation.

For thus lowering the casting 164 there is adjustably secured to the casting by screws 504 (FIGS. 4 and 10) an arm 506 which is pivotally connected by a screw 508 to one end of a link 510, the other end of which is pivotally connected by a screw 512 to a bell crank lever 514 which is pivoted at 516 on a bracket 518 secured to the machine head. The bell crank lever 514 is connected by a

rod 520 to the armature 522 of a solenoid 524 connected in the circuit of the microswitch 392 which, it will be recalled, is closed upon depression of the treadle 148, to operate the valve 374 to admit adhesive into the extrusion nozzle 172. Closing of the microswitch 392 energizes the solenoid 524 and, through the mechanism above described, causes the casting or strip feed assembly 164 to be moved downwardly toward the nozzle 172. The casting 164 is returned to its elevated position when the solenoid 524 is deenergized at the conclusion of a cycle of operations by a spring 526 attached at its lower end to the pin 512 and at its upper end to a bracket 528 secured to the bracket 216.

Margin Control Means

The machine is provided with an edge gage 530 (FIGS. 1, 4, 19 to 22, and 25) resting on the top of the insole supporting table roll 64 and engaged by the edge face of the insole both at the beginning and during the course of a strip attaching operation. The edge gage is movable at determined times in the course of a strip attaching operation transversely of the insole to shift the insole laterally of the roll 64 so as to vary the widthwise position of the insole relative to the presser foot and thereby vary the distance from the insole edge at which the strip will be attached at different localities along the periphery of the insole, notably in the shank, forepart, and toe portions of the insole. In rib attaching machines as constructed heretofore the edge gage is shifted manually by the operator. Besides requiring considerable skill and alertness on the operator's part to shift the gage at the proper times, such manipulation of the edge gage also results in slowing the operation. In accordance with an important feature of the present invention, mechanism is provided in the illustrated machine for shifting the edge gage automatically as the attachment of a strip progresses around the periphery of an insole to cause the strip to be attached at predetermined variable distances from the insole edge in accordance with the style of the shoe in which the insole is to be incorporated.

The edge gage 530 is secured for adjustment in the direction of feed of the work by a screw and slot connection 532 to a block 534 (FIGS. 20, 21 and 22) slidably laterally of the direction of feed of the work in a guideway 536 formed in a bracket 538 fixed to the table 62 by a screw 540. A pin 542 extending rearwardly from an upstanding arm of the block 534 has mounted on it a square block 544 engaging between the arms of the U-shaped upper end portion of a block 546 adjustably secured by a screw 548 to a rearwardly extending arm 550 of a slide 552 movable laterally of the machine in a guideway 554 provided in a bracket 556 secured to the machine head 54. By this arrangement the edge gage is permitted to move relative to the block 546 with the table 62 when the latter is lowered, as earlier explained, to facilitate the insertion of an insole between the roll 64 and the presser foot 100. In the upper face of the arm 550 of the slide 552 there is provided a groove 558 along which the block 546 may, after loosening the screw 548, be moved forward or rearward of the machine to adjust the initial position of the edge gage 530 on the roll 64, the gage being fixed in the adjusted position by the screw 548. An adjustable extension 560 is connected to the outer or right-hand end of the slide 552 by a binding screw 562 extending through a slot 564 in the extension 560.

The outer, or right-hand end of the extension 560 abuts against the bifurcated rear end portion 566 of an arm 568 mounted for swinging movement in a horizontal plane about a stud 570 threaded into the upper end of a bracket 572 secured to the machine head 54. A pin 576 mounted in the portion 566 of the arm 568 carries a roll 578 which is normally maintained in engagement with the periphery of a cam plate 580 by a spring 582 (FIG.

19) attached at one end to a pin 534 extending rearwardly from the extension 560 of the slide 552 through a slot 586 provided in the slide 552. At its other end the spring is attached to a pin 588 fastened in the machine head. This pin-and-slot connection between the slide 552 and the extension 560 permits moving the slide 552 to the left or to the right relatively to the extension 560 in order to locate the edge gage in the desired position on the insole supporting roll 64, while always maintaining the extension 560 in engagement with the arm 568.

The cam 580 is pinned to a vertical shaft 590 (FIGS. 1, 5 and 8) rotatably mounted in a cylindrical bearing member or boss 592 formed integral with a bracket 593 secured to the machine head 54. Also pinned to the shaft 590 is a gear 594 meshing with a pinion 596 on the lower end of a vertical shaft 598 rotatable in bearing brackets 600, 602 secured to the machine head. A bevel gear 604 pinned to the upper end of the shaft 598 is arranged to mesh with either of a pair of level gears 606, 608 spaced from each other by a sleeve 610 on a horizontal shaft 612 which is supported at its outer end for rotary and axial movement in a bracket 614 fixed to the machine head. The inner, or left-hand end of the shaft 612 is splined to a shaft 616 rotatably mounted in bearing brackets 618, 620, 622 secured to the machine head. A peripheral groove formed in the sleeve 610 is engaged by a block 623 (FIG. 5) to which is secured the lower forked portion of an arm or lever 624 pivotally secured by a screw 626 to a bracket 628 extending upwardly from the machine head. At its upper end the arm 624 is provided with a knob 630 by which the arm may be moved in a clockwise or counterclockwise direction above the screw 626 to move the shaft 612 to the left or to the right to move the gear 606 or the gear 608 into meshing engagement with the gear 604. The knob 630 is mounted on the outer end of a spring-pressed pin 632 (FIG. 8) which extends through the arm 624 and is arranged to engage in either of two holes 634 provided in the bracket 628 to lock the arm in its selected position.

Keyed to the shaft 616 is a one-way roller clutch 636, 638 (FIGS. 1 and 5), of which the member 638 is connected to a pin 640 carried by a forwardly projecting arm 642 fixed by screws 644 to a plate 646 secured by cap screws 648 to the top of the bracket 620. Also keyed to the shaft 612 is a similar clutch 650, 652, of which the member 652 is pivotally connected by a pin 654 to the forward end of a cross link 656 pivotally connected at its rear end by a pin 658 to one arm of a bell crank lever 660 pivoted at 662 on the machine head. The other arm of the bell crank lever 660 is pivotally connected by a pin 666 to the upper end of an arm 668, the lower end of which is pinned to a shaft 670 on which is mounted the rear end of a cross link 672. At its forward end this link is pivotally connected by a pin 674 to the upper end of a bar 676 pivoted about midway of its length on the shaft 310 and at its lower end on the shaft 242 about which the presser foot bar 240 swings.

Through the above-described connections, as the bar 240 is actuated by the eccentric 302 to impart intermittent feeding movement to the presser foot 100, the cross link 656 reciprocates the clutch member 652 on the shaft 616 to rotate this shaft and the shaft 612 in one direction to rotate the cam 580 intermittently in timed relation to the operation of the presser foot to feed the insole. During reverse rotation of the clutch 650, 652 the clutch 636, 638 acts as a brake to hold the shafts 616, 612 against reverse rotation.

As stated earlier, the main shaft 266 of the machine and the eccentrics 264 and 302 secured to it are rotated at a constant speed and operate the presser and feed foot 100 through the connections between the eccentrics and the bar 240 to which the foot is attached, com-

prising the pairs of double yokes or links 280, 282 and 312, 314 and their associated connecting rods 258 and 308 with which, as previously explained, they constitute toggle arrangements. It will be recalled that while the double yokes or links are in substantial alinement with their respective connecting rods, rotation of the eccentrics merely reciprocates the toggle joints without producing any appreciable vertical or horizontal movement of the presser and feed foot, such movement being imparted to the foot to press the strip and feed the work when the toggles are broken by depression of the treadle 148. As also explained previously, while the eccentric 264 imparts to the presser foot substantially uniform vertical reciprocating movement to cause it to apply the strip to the insole with uniform pressure, the length of the horizontal component of movement imparted to the presser foot by the eccentric 302, and hence the rate of feed of the work, may be varied by varying the angular displacement of the double yokes 312, 314 with relation to the rod 308, without affecting the uniform vertical or strip pressing component of movement of the presser foot. This arrangement enables the operator to vary the rate of work feed at will according to differences in style characteristics of the shoes in which the insoles are to be incorporated and which may have pointed, rounded, or square toes.

It will be evident that as the length of the feed strokes of the presser foot is increased or decreased, the speed at which the insole will be fed through the machine will be correspondingly increased or decreased. It will also be evident that if the feed control means above described is set to feed the work with strokes of a given length, the presser foot will require a greater number of impulses to operate around a large insole than would be required to operate around a small insole. It is of the utmost importance, however, that the rotation of the cam 580 be so coordinated with the feed of the work that it will complete a revolution in the time required to attach a strip around an insole, whatever the size of the insole or the rate of feed may be. Synchronizing the speed of rotation of the cam with the speed of the work feed is important, not only to insure that the cam will actuate the edge gage 530 to shift the insole so as to vary the marginal location of the strip on the insole at the appropriate points, as described above, but also because the cam, upon completing a revolution, actuates means to be described shortly which automatically stop the attaching operation, and also other means which operate a knife to sever the strip.

For thus synchronizing the rotation of the cam 580 with the feeding movements of the presser foot to feed the work at any determined rate, the following arrangement is provided in the illustrated machine. On the shaft 670 (FIG. 5) is secured the lower end of a vertical arm 678 the upper end of which is mounted for swinging movement about a horizontal axis on a pin or shaft 680 to which is secured the upper end of a second arm 682 the lower end of which is pinned to a shaft 684 which is supported in a bracket 686 formed on the machine head, and which is in axial alinement with the shaft 670. The shaft 684 extends beyond the bracket 686 and has secured to its outer end the lower end of an arcuate arm 688 (see also FIG. 23) the upper end of which is connected to the rear end of a forwardly and downwardly inclined arm 690 by means of a stud 692 extending through a slot 694 in the arm 690. The forward end of the arm 690 is secured to the outer end of the shaft 284 connecting the yokes 280 and 282 which, as earlier explained, are swung forwardly out of the position of vertical alinement with the rod 258 by depression of the treadle 148 to start operation of the presser foot 100. By such movement of the yokes 280, 282 the arm 690 is moved forward, or to the right of FIG. 23, rotating the shaft 684 in the same direction to swing the arms 682 and 678 into a position of angular relation to the vertical bar 676. With the arms

so positioned, oscillatory motion of the presser foot bar 249 about the axis of the shaft 242 to impart to the presser foot its horizontal feeding component of movement will also oscillate the bar 676 which is pivoted on the same shaft and, through the connections between this bar and the clutch member 652, will rotate the shafts 616, 612 by intermittent steps to rotate the cam 580 at speeds variable according to the extent of angular displacement of the arms 678, 682 relative to the bar 676.

As stated previously, for a selected length of feed stroke, the presser foot will execute a greater number of impulses in operating around a large insole than would be required to operate around a small insole. The cam must, accordingly, be rotated at a faster rate for a small insole and at a slower rate for a large insole, in order that it may complete a revolution in the time required to attach a strip from the heel breast line at one side of the insole to the heel breast line at the opposite side. Hence, the extent of angular displacement of the arms 678, 682 must be varied according to the size of the insole to which a strip is to be attached.

For thus determining the extent of angular movement of the arms 678, 682 to determine the rate of speed at which the cam 580 will be rotated for insoles of a given size, there is provided an adjustable limiting screw 696 (FIG. 23) which is arranged to be engaged by the upper end of the arcuate arm 688 when this arm is rotated, as previously explained, by the forward and downward movement of the arm 690. The screw 696 extends through an upstanding member 697 formed integral with a bracket 698 secured to the top of the machine head, and has secured to its forward end a dial plate 700 (see also FIG. 1) and a knob 702 by which it may be rotated to bring any one of a plurality of size markings provided on its front face into register with a pointer or index finger 704 mounted in a slideway 706 in the bracket 698. To the stud 692 is attached one end of a spring 708 (FIGS. 5 and 23), the other end of which is attached to a pin 710 projecting from the arm 690. The arrangement is such that when, by depression of the starting treadle, the pairs of yokes 280, 282 and 312, 314 are moved into the position in which the eccentrics 264 and 302 are rendered effective to impart pressing and feeding movements to the presser foot 100, the arm 690 is moved forwardly and downwardly and the arm 688 is swung forwardly (or clockwise with reference to FIG. 5) until stopped by engagement of its upper end with the limiting screw 696. By movement of the arm 688 into that position the arms 678, 682 are swung into an angular position with relation to the vertical bar 676 in which the cam 580 will be rotated at a rate of speed appropriate for insoles of a given size as determined by the adjustment of the limiting screw for that particular size. Thereafter, upon further depression of the treadle to impart to the presser foot feeding movements of greater length, the arm 690 will be moved in a downward and forward direction, until stopped by engagement of the rear end of the slot 694 in the arm with the stud 692 carried by the arm 688. During such additional forward movement of the arm 690, the spring 708 will yield and the stud 692 will move relatively to the slot 694, so that this movement of the arm is merely lost motion which has no effect on the setting of the arms 678, 682. Thus the rate of feed of the insole by the presser foot may be varied at the will of the operator without affecting the rate at which the cam will be rotated in accordance with the setting of the dial 700 for a selected insole size.

The manner in which the cam 580 actuates the edge gage 530 during a strip attaching operation to shift the insole laterally on the supporting roll 64, so as to vary the distance from the insole edge at which the strip will be applied along different portions of the insole, may best be understood by reference to FIG. 24, in which the cam is shown in its normal or starting position, and FIG. 27 which shows a completed insole for a right shoe. As will

be observed by examining the last-mentioned figure, the four areas where substantial variations in the location of the strip occur are the outside shank, the outside ball portion, the inside ball portion, and the inside shank. Thus, along the outside and inside shank portions the strip curves inward a certain distance to leave a wide margin of the insole for the lasting and inseaming operations to be performed; along the outside and inside ball or forepart portions the strip is laid substantially flush with the insole edge.

The location of the strip may, of course, vary with different shoe style characteristics, and the cam may accordingly be shaped to conform to any particular insole contour. Thus, the cam illustrated in FIG. 24 has been formed with two lobes or raised portions 711, 712 which moves the edge gage to shift the insole so that the strip will be laid at or close to the edge of the insole, and two low portions 713, 714 which cause the edge gage and the insole to be moved to a position in which the strip will be laid further inward from the insole edge. Since, however, style characteristics may vary from one shoe factory to another, or even within the same factory, a different cam would be required for each shoe style, which would be obviously undesirable because of the increased cost of carrying several cams and the loss of time involved in changing cams. To obviate the need of a different cam whenever the machine is to operate on insoles for shoes of a different style, provision is made, in the illustrated machine, for adapting to the cam 580 detachable and interchangeable auxiliary cam members 716, 718, 720, 722 which may be secured to the main cam in adjustable positions by means of screws 724, 726, 728, 730 extending through slots 732, 734, 736, 738 in the cam members and engaging in an annular groove 740 in the upper surface of the cam 580. By adjusting the cam members relatively to each other and to the cam 580, it is possible to lengthen or shorten the lobes on the cam so as to vary the points at which the inward swing of the strip is to begin and end, and thus vary the linear distance along the periphery of the insole which the strip will be attached at or close to the insole edge.

It will be assumed that an insole for a right shoe has been placed on the supporting roll 64 and the arm 624 has been turned to the left, as shown in FIGS. 1 and 5, to shift the gear 608 on the shaft 610 to the right into meshing engagement with the gear 604 on the shaft 598. As earlier explained, the insole is introduced into the machine heel end foremost, and is located by the heel gage 116 in the lengthwise position relative to the presser foot at which the attaching operation is to start. Usually the starting point is the heel breast line of the insole, and in the case of an insole for a right shoe, the starting point will be the heel breast line at the outside margin of the insole. When the starting treadle 148 is depressed to begin an attaching operation, the cam 580 will be rotated clockwise from its starting position shown in FIG. 24, and during the first part of the rotation of the cam the roll 578 will be engaged by the portion of the cam comprised between the radii $a-b$ (or $a-b'$ if the cam member 716 has been adjusted in the position shown in FIG. 24). Accordingly, during this part of the rotation of the cam, the strip will be laid at some distance inward of the insole edge along the outside shank portion until the lobe 711 of the cam (or the raised portion of the auxiliary cam member 716) engages the cam roll 578 and moves the edge gage 530 inward or to the left, as seen in FIG. 25, to shift the insole laterally into a position in which its edge is closer to the presser foot. While the cam roll 578 is in engagement with the portion of the cam comprised between the radii $b-c$ (or $b'-c'$), the strip will be attached at or close to the insole edge along the ball portion until the roll is engaged by the low portion 713 of the cam at about the tip line of the insole. While the roll is in engagement with this cam portion, comprised between the radii $c-d$ (or $c'-d'$), the strip will be attached around the toe portion at a slight distance

inward from the insole edge by reason of the slight drop of the cam at this side. After the attachment of the strip around the toe end to the tip line at the inside margin of the insole, the roll is engaged by the second lobe 712 of the cam and while it traverses the cam portion comprised between the radii $d-e$ (or $d'-e'$) the strip will be attached along the ball portion of the insole along the inside margin at or close to the edge until, at point e (or e'), the roll is engaged by the low portion 714 of the cam comprised between the radii $e-a$ (or $e'-a$), and the edge gage is moved rearward or to the right of FIG. 25, so that the insole will be located in the position in which the presser foot will attach the strip at a certain distance from the insole edge along the inside shank portion to a point located at the heel breast line substantially in alignment with the point at which the strip was first attached. When the operation reaches that point, the cam will have completed a revolution and returned to its neutral or starting position.

It will be understood that when the machine is set for operating on insoles for left shoes, the operation will start at the heel breast line along the inside margin of the insole and the above-described sequence of operations of the cam, which will be rotated counterclockwise, will be reversed.

Holddown Mechanism

During the attachment of a strip the presser foot, as earlier explained, is moved through an orbital path normal to the plane of the insole, with a downward motion to press the strip, a forward motion to feed the insole with the attached strip, and an upward and rearward motion to repeat its cycle. To guard against back feed of the insole during the interval when the presser foot is out of engagement with it, there is provided a holddown 742 (FIGS. 4, 5 and 7) having a tooth 744 for engaging the inner flange of the composite ribbed strip. The holddown 742 is mounted for heightwise movement in a slide-way 746 provided in a block or bracket 748 secured to a bracket 750 fixed to the boss 247. The holddown is maintained in its normal elevated position by an L-shaped latch or lever 752 pivoted on a pin 754 set in a block 756 which is fixed to a bracket 758 secured to the bracket 132 in which the heel gage slide 130 is movable (see FIG. 6). The upper end of the vertical arm of the lever 752 is in engagement with the roll 134 on the rod 138 by which the slide 130 is lifted to raise the heel gage 116 when the starting treadle 148 is depressed to begin an attaching operation. A spring 760 attached at one end to the lever 752 and at its other end to a pin 762 on the bracket 758 maintains the horizontal arm of the lever 752 in latching engagement with an angle bracket 764 secured to the holddown 742.

When the starting treadle is depressed and the roll 134 is moved out of engagement with the vertical arm of the lever 752, this lever swings counterclockwise, as seen in FIG. 7, and releases the holddown 742 to the action of a spring 766 attached at one end to a bracket 768 secured to the bar 676 (see FIG. 5) and at its other end to a pin 770 extending through a slot 772 in the lower end of a downwardly extending arm 774 mounted on the shaft 242, the pin 770 being set in an arm 776 mounted for rocking motion about a pin 778 mounted in a bracket 780 secured to the block 748. The ball-shaped rear end of the arm 776 engages in a recess 782 formed in the holddown 742. Through the above-described connections, as the bar 240, to which the presser foot 100 is attached, is moved upward to raise the presser foot from the work as it is returning to its starting position and the arm 774 is moved in the same direction, the arm 776 is caused to rock in a counterclockwise direction, as seen in FIG. 5, and lowers the holddown 742 to cause its tooth 744 to engage the strip on the insole and maintain the insole against retrograde movement. During the downward movement of the presser foot to press the strip and feed

the work, the downward movement of the arm 774 rocks the arm 776 in a clockwise direction to raise the hold-down 742 from the insole.

Automatic Work Feed Stopping and Strip Severing Means

When the cam 580 reaches its starting position after completing a revolution which, as earlier noted, coincides with the operation of the presser and feed foot 100 around the periphery of an insole, it actuates means by which the lever 142 which controls the operation of the foot is caused to return to its inoperative position, thereby automatically stopping the attachment of the strip and the feed of the insole at a predetermined point at the heel breast line of the insole, which is substantially in transverse alignment with the point where the attachment of the strip was started.

Referring to FIGS. 8 and 9, the upper section 146 of the two-part rod connecting the lever 142 to the operating treadle 148 is connected at its lower end to the rear or left end of an L-shaped arm 784 which is pivoted at 786 on the machine head or casting 54. The lower section 147 of the treadle rod, the lower end of which is attached to the treadle, is attached at its upper end to the rear end of a latch member 788 which is pivotally secured about midway of its length by a stud 790 to the arm 784 and is provided at its right-hand end with a shoulder 792 which is normally engaged by a notch or shoulder 794 formed on the upper end portion of one arm of a bell crank 796 which is pivotally secured by a stud 798 to the lower end of the downwardly projecting portion of the L-shaped arm 784. The other arm of the bell crank 796 is provided in its right-hand end, as seen in FIG. 9, with a slot 800 which receives a pin 801 pivotally connecting to this arm the upper end of a link 802, the lower end of which is pivotally connected to the armature 804 of a solenoid 806 supported on a bracket 808 fastened to the machine head 54. With the shoulder 792 of the latch member 788 in engagement with the shoulder 794 of the bell crank 796, when the treadle 148 is depressed to start an attaching operation, the two treadle rod sections 146, 147 are moved downward as a unit and the arm 784, the latch member 788, and the bell crank 796 are swung in unison in a counterclockwise direction, as seen in FIG. 9.

The arrangement is, however, such that when the cam 580 reaches its neutral or starting position after completing a revolution, a block 810 (FIGS. 1, 8 and 24) secured in adjustable position to the upper surface of the cam engages a roll 812 carried by an arm 814 of a microswitch 816 which is supported on a bracket 818 secured to the machine head. This microswitch is a two-position switch and prior to engagement of its arm by the block 810 is in a down position, as viewed in FIG. 28, in which it closes a circuit through the coil of a relay K2, as long as a microswitch 820 in series with the switch 816 is in its normally closed position. Energization of relay K2 closes contacts K2A and K2B, the latter contacts closing a holding circuit through the relay K2 when the switch 816 is moved to its up position, as viewed in FIG. 28, by the block 810, as long as the switch 820 remains closed.

Upon operation of the switch 816 by the block 810, and its movement into the position shown in FIG. 28, a circuit is closed through the solenoid 806 through the relay contacts K2A. Energization of this solenoid causes the bell crank 796 to swing clockwise, as seen in FIG. 9, about the pivot 798, against the tension of a spring 822 attached at one end to the bell crank and at its other end to a pin 824 projecting from the arm 784, which spring tends normally to maintain the shoulder 794 of the bell crank in engagement with the shoulder 792 of the latch member 788. Clockwise movement of the bell crank disengages it from the latch member, thereby breaking the connection between the two treadle rod sections 146, 147 and releasing the upper rod section 146 to the action of a spring 826 attached at its upper end to the machine frame and at its lower end to a pin 828 projecting from

the rod 146, to move this rod upward and swing the lever 142 to which it is attached in a counterclockwise direction, as seen in FIG. 8, whereby the pairs of double yokes 280, 282 and 312, 314 are returned to their neutral positions to render the presser foot inoperative, even if the operator continues to hold the treadle down. As the upper rod section 146 is moved upward, the arm 784 is swung in a clockwise direction, as seen in FIG. 9, about the pivot 786, while the latch member 788 is swung counterclockwise about its pivot 790, if the treadle 148 is at that time still held in the down position by the operator.

As the arm 784 swings clockwise, it closes a normally open microswitch 830 (FIG. 9) to close a circuit including the switches 820, 816 and relay contacts K2A through a solenoid 832 (FIGS. 1, 4 and 25) supported on the machine head to operate a knife 834 which severs the strip at the heel breast line where the strip was last attached to the insole. As shown in FIGS. 1 and 25, the knife 834 is secured to a slide 836 movable in a direction transverse to the insole in a slideway provided in a member 838 secured to the machine head 54. A forwardly projecting pin 840 in the slide 836 engages in a slot 842 provided in the upper end of one arm of a bell crank lever 844 pivoted at 846 on the machine head, the other arm of the lever being connected by a link 848 to the armature 850 of the solenoid 832. When the solenoid is energized by closing of the microswitch 830, movement of the bell crank 844 in a counterclockwise direction moves the slide 836 and the knife 834 forward, or to the left of FIGS. 1 and 25, to sever the strip. At the end of the forward stroke of the knife, an upwardly projecting lug 852 of the knife slide 836 opens the previously mentioned normally closed microswitch 820, thus deenergizing the coil of the relay K2, causing opening of the contacts K2A, K2B, and deenergizing the solenoids 806 and 832. Deenergization of the solenoid 806 permits the spring 822 to swing the bell crank 796 counterclockwise, as seen in FIG. 9, to the position in which its shoulder 794 will be reengaged by the shoulder 792 of the latch member 788 when the operator releases the treadle 148. Counterclockwise movement of the bell crank 796 is limited by a stop pin 853 mounted in the downwardly projecting portion of the arm 784. Deenergization of the solenoid 832 permits the knife slide 836 and the knife 834 to be retracted to the starting position by a spring 854 (FIGS. 1 and 25) attached at one end to the pin 840 and at its other end to an upright 856 fixed to the machine head, this movement of the knife slide being limited by engagement of the bell crank 844 with a stop screw 858 threaded through a post 860 bolted to the machine head.

When, at the end of an attaching operation, the operator releases the treadle 148, the lower treadle rod section 147 is moved upward by a spring 862 (FIG. 2) attached at its lower end to the treadle and at its upper end to the machine base 50. As the treadle is thus raised and the lower treadle rod section 147 is moved upward, the latch member 788 (FIG. 9) which, when the lever 796 was swung clockwise to disengage it from the latch member and while the treadle was still held depressed by the operator, was swung counterclockwise about the pivot 790 to a position in which its shoulder 792 was located above the shoulder 794 of the lever 796, is now swung clockwise and cams the lever so as to cause the shoulder of the latch member to reengage the shoulder of the lever for a succeeding operation.

Description of Operation of Machine

The operation of the various mechanisms of the machine has already been explained in detail in the course of the foregoing description. It may, however, be useful to give a summary of an operating cycle of the machine.

It will be assumed that prior to starting the operation of the machine to process a given lot of insoles, the following preliminary adjustments will have been made. The table 62 (FIG. 1) has been positioned, by rotation of the

adjusting screw 104 (FIG. 2), at the proper level in accordance with the thickness of the insoles; the heel gage 116 (FIG. 4) has been located in the proper position transversely of the machine to determine the point where the attachment of the strip is to begin; the arm 624 (FIG. 1) has been turned to the left or the right to engage either the beveled gear 608 or the beveled gear 604 with the beveled gear 604 at the upper end of the shaft 598 for rotation of the cam 580 in one direction or the other according to whether the insoles to be operated upon are for right or left shoes; the dial 700 has been set for the particular size run to determine in advance the speed of rotation of the cam; the limit stop screw 332 (FIG. 8) has been adjusted to determine in advance the limit of clockwise movement of the lever 142 (FIG. 8) and hence the maximum rate of feed of the work by the presser foot 100 (FIGS. 4 and 5); and the edge gage 530 (FIGS. 1, 20 and 25) has been located in the desired position axially of the work supporting surface of the roll 64 mounted in the table.

The motor 276 having been started and the appropriate switches turned on to supply current to the various heating units mounted in the cement melting unit 350, the nozzle housing 368 and the extrusion nozzle 172, to attach to an uncoated insole blank a rib strip the attaching flanges of which are similarly uncoated, the operator will first depress the treadle 82 (FIG. 2) to lower the table 62 and place the insole blank on the roll 64, with the heel end of the blank against the heel gage 116. The operator will next depress the treadle 148, whereupon the heel gage will be raised out of engagement with the insole blank and at the same time the lever 142 will be swung clockwise from its inoperative position, as shown in FIG. 8, and by disengagement of the pin 493 on the lever from the roll 494 carried by the arm 496 of the microswitch 492, will close this switch and energize the solenoid 490 which, through the link 480, will actuate the clutch 470 to rotate the shaft 442 to cause the rod cement feeding mechanism to feed a length of cement rod into the melting unit 350 so as to insure an adequate supply of molten cement for coating the flanges of the leading end of the rib strip in advance of the operation thereon by the presser foot 100.

Continued clockwise movement of the lever 142 to its fully operative position, as determined by the engagement of the abutment member 331 carried by the lever with the limit stop screw 332, will swing the pairs of double yokes or links 280, 282 and 312, 314 out of axial alignment with the rods 258, 308 with which they respectively form toggle arrangements. By the swinging movement of the pair of yokes 280, 282 the finger 396, which is pinned to the shaft 286 (FIGS. 4 and 5) to which is also pinned one arm of the outer yoke 282, is disengaged from the roll 394 carried by the arm of the normally closed microswitch 392, permitting this switch to close and energize the solenoid 390, whereby the valve 374 (FIG. 10) is rotated to the position in which its orifice 372 communicates with the inclined passageway 366 in the nozzle housing 368 to permit molten cement to flow from the melting unit 350 through the passageway 366 and into the extrusion nozzle 172. Closing of the microswitch 392 also energizes the solenoid 524 (FIG. 4) to lower toward the extrusion nozzle the strip feeding assembly 164, which is normally held in a position raised from the heated nozzle to prevent softening of the adhesive by which the plies of the rib portion of the strip are bonded together.

Movement of the pairs of double yokes or links 280, 282 and 312, 314 (FIG. 5) out of axial alignment with the rods 258, 308, as above explained, breaks the toggle formed by each pair of yokes with the associated rod, so that thereafter rotation of the eccentrics 264 and 302 on the main shaft 266 will make and break the toggles to reciprocate the bar 240 vertically and horizontally so as to impart to the presser foot 100 attached to it movement in an orbital path, with a vertical component to press the

strip against the insole blank and a horizontal component to feed the blank after attachment of each successive portion of the strip, at rates variable according to the extent to which the double yokes are displaced angularly from their positions of axial alignment, as determined by the degree of pressure exerted by the operator on the treadle 148.

Through the connections between the presser foot bar 240 and the strip feeding mechanism, including the cross link 238, the horizontal shaft 210, the beveled gears 218 and 220, and the vertical shaft 202 to which the gear 198 (FIG. 10) is attached, the feed rolls 176, 178 are rotated by the reciprocatory horizontal movement of the bar 240 to feed the rib strip along the inclined upper surface of the extrusion nozzle 172 toward engagement with the insole blank in timed relation to the feed of the work by the presser foot. Also, through the connections between the bar 240 and the rod cement feeding mechanism, including the cross link 404 (FIGS. 4 and 18) and the clutches 438, 440, the shaft 442 is rotated to drive the feed wheels 344, 346 to feed the solid rod of cement into the melting unit 350 in timed relation to the feed of the work by the presser foot and also to rotate the melting disk 356 within the melting unit to cause the molten cement to be delivered to the nozzle housing 368 and thence, through the inclined passageway 366, to the extrusion nozzle 172 to coat the successive portions of the flanges of the strip, as the strip travels over the tapered inner edge of the nozzle, with heated liquid cement extruded through the capillary grooves 403 (FIG. 16) provided in the nozzle.

The attachment of the strip usually begins at a point on the heel breast line at one side of the insole and proceeds along that side in the direction of the toe portion and, after rounding this portion, continues along the opposite side to a point at the heel breast line substantially in transverse alignment with the starting point. During the progress of the attaching operation the operator will guide the insole by maintaining its edge face against the edge gage 530 (FIGS. 1, 20 and 25), which is shifted by the cam 580 axially of the roll 64 to vary the relation between the insole edge and the presser foot so as to cause the strip to be attached at varying distances from the insole edge along different portions of the insole. Through the train of connections between the cam shaft 590 and the presser foot bar 240, including the clutch 650, 652 (FIG. 5), the cross link 656, the bell crank 660, the arcuate link 672, and the vertical bar 676 which is oscillated with the bar 240 about the horizontal shaft 242, the cam is rotated in timed relation to the feed of the insole by the presser foot and at a rate of speed determined by the setting of the dial 700 in accordance with the size of the insole, so that a rotation of the cam through 360° will coincide in time with an operation around the insole from the starting to the finishing point.

When the cam reaches its starting position after completing a revolution, the block 810 (FIG. 1) mounted on the cam moves the arm of the microswitch 816 to the position shown in FIG. 28 and energizes the solenoid 806 (FIGS. 4 and 9) to disengage the arm 784 to which the upper treadle rod section 146 is attached from the latch member 788 to which the lower section 147 is attached, whereupon the upper rod section 146 is moved upward by its spring 826, to return the lever 142 (FIG. 8) to its inoperative position and automatically stop the operation of the presser foot. As the treadle rod section 146 is moved up and the arm 784 to which it is connected swings clockwise with reference to FIG. 9, it closes the microswitch 830 to energize the solenoid 832 (FIG. 1) which operates the knife 834 to sever the strip. As the knife reaches the limit of its operative stroke, the normally closed microswitch 820 is opened by the lug 852 projecting from the knife slide 836, whereby the solenoids 806 and 832 are deenergized to permit the spring 822 (FIG. 9) to move the bell crank 796 into position to be reengaged by the latch member 788 and reconnect the two

treadle rod sections 146 and 147, and also to permit the spring 854 (FIG. 1) to return the knife to its initial position.

When the lever 142 (FIG. 8) is swung back to its initial position, as above described, the double yokes 280, 282 are swung back to their original positions and the finger 396 (FIG. 4) is returned to the position in which it again opens the microswitch 392 to deenergize the solenoid 390 and permit the spring 398 to move the rack bar 380 in the direction to rotate the valve 374 to the position in which its orifice 372 is out of communication with the passageway 366 in the nozzle housing 368, so as to stop extrusion of cement from the nozzle 172. Opening of the switch 392 also deenergizes the solenoid 524 to permit the spring 526 to move the strip feeding assembly 164 upward away from the extrusion nozzle 172.

The various operating mechanisms of the machine are at this time restored to their respective initial positions in readiness for a succeeding attaching operation.

Having thus described my invention, what I claim as new and desire to secure by Letters Patent of the United States is:

1. In a machine for adhesively attaching to an uncoated insole a strip having a rib portion and uncoated oppositely extending attaching flanges, a support for the insole, a foot for pressing the strip against the insole margin to bond it thereto and for feeding the combined insole and attached strip, power driven means for imparting to the foot movement in an orbital path with components of movement in one direction to press the strip against the insole and in another direction to feed the insole and attached strip, means for supporting a supply of ribbed strip material, means operated intermittently by the power driven means in timed relation to the feeding movements of the pressing and feed foot to feed successive portions of strip material into engagement with the insole, strip guiding means including a nozzle along which the strip is moved toward the insole, means for holding a supply of adhesive for coating the strip flanges as the strip is moved along said nozzle, means operated intermittently by the power driven means in timed relation to the feeding movements of the foot to feed adhesive from the source of supply to the nozzle and cause adhesive to be extruded through openings therein to coat the insole engaging surfaces of the strip flanges, an edge gage engageable with the edge face of the supported insole to guide the insole during an attaching cycle, means operated intermittently by the power driven means in timed relation to the feeding movements of the foot to cause the edge gage to shift the insole laterally of the support to vary the location of the strip along the insole margin, means actuated by said edge gage operating means for automatically stopping the operation of the foot, of the strip feeding means and of the adhesive feeding means at a predetermined point on the insole independently of the power driven foot operating means, a knife for severing the strip at the end of an attaching operation, and means actuated by the means for stopping the feeding movement of the foot to operate the knife.

2. In a machine for adhesively attaching to an uncoated insole a ribbed strip having a rib portion and uncoated attaching flanges, a support for the insole, a foot for pressing the strip against the insole margin to bond it thereto and for feeding the combined insole and attached strip, power driven means for imparting to the foot movement in an orbital path with components of movement in one direction to press the strip against the insole and in another direction to feed the work, means for supporting a supply of ribbed strip material, strip guiding means including a nozzle along which the strip is moved toward the insole, means connected to the pressing and feed foot and operated thereby intermittently in timed relation to its feeding movements to feed successive portions of the strip into engagement with the insole, means for holding a supply of adhesive for coating the strip flanges as the strip is moved along said nozzle, means connected to the press-

ing and feed foot and operated thereby intermittently in timed relation to its feeding movements to feed adhesive from the source of supply to the nozzle and to cause adhesive to be extruded through openings therein to coat the insole engaging surfaces of the strip flanges, an edge gage engageable with the edge face of the supported insole to guide the insole during an attaching cycle, means connected to the pressing and feed foot and operated thereby intermittently in timed relation to its feeding movements to cause the edge gage to shift the insole laterally of the support to vary the location of the strip along the insole margin, and means actuated by said edge gage operating means for automatically stopping the operation of the foot, the strip feeding means and the adhesive feeding means at a predetermined point on the insole independently of the power driven foot operating means.

3. In a machine for adhesively attaching a ribbed strip to an insole, a support for the insole, means for directing the strip toward the insole, means for progressively attaching the strip at variable distances from the marginal edge of the insole and for feeding the insole over the support, an edge gage associated with the support for controlling the position of the insole laterally of the support and of the point of application of the strip relative thereto, and power-operated means for moving said edge gage laterally of the support in accordance with a predetermined cycle.

4. In a machine for adhesively attaching a ribbed strip to an insole, a support for the insole, means for directing the strip toward the insole, means for attaching the strip to successive portions of the margin of the insole, power-operated means for actuating said attaching means, an edge gage associated with the support for guiding the insole relatively to said attaching means during an attaching operation, and means operated by said power-operated means for moving the edge gage laterally of the support in accordance with a predetermined cycle to vary the position of the insole relative to the attaching means, thereby to vary the point of application of the strip relative to the edge of the insole.

5. In a machine for adhesively attaching a ribbed strip to an insole, a support for the insole, means for directing the strip toward the insole, means for attaching the strip progressively to the margin of the insole, power-operated means for actuating said attaching means, an edge gage associated with the support for guiding the insole relatively to said attaching means during an attaching operation, means operated by said power-operated means for moving the edge gage laterally of the support in accordance with a predetermined cycle to vary the position of the insole relative to the strip-attaching means thereby to vary the point of application of the strip relative to the edge of the insole, and means for controlling the operation of said edge gage moving means in accordance with differences in the sizes of insoles to be operated upon in the machine.

6. In a machine for attaching a strip to an insole, a support for the insole, a member for attaching the strip to the insole margin and feeding the combined insole and attached strip, power driven means for imparting to the member movement in an orbital path with components of movement in one direction to attach the strip and in another direction to feed the insole and attached strip, means connected to said member and operated intermittently in timed relation to the feeding movements thereof to feed the strip toward the insole, an edge gage associated with the support and engageable with the edge face of the insole to guide the insole during an attaching cycle, and means connected to the attaching and feeding member and operated in timed relation to the feeding movements thereof to vary the position of the edge gage laterally of the support thereby to vary the point of application of the strip relative to the edge of the insole.

7. In a machine for attaching a strip to an insole, a support for the insole, a member for attaching the strip

to the insole margin and feeding the combined insole and attached strip, power driven means for imparting to the member movement in an orbital path with components of movement in one direction to attach the strip and in another direction to feed the insole and attached strip, means connected to said member and operated intermittently in timed relation to the feeding movements thereof to feed the strip toward the insole, an edge gage associated with the support and engageable with the edge face of the insole to guide the insole during an attaching cycle, edge gage operating means connected to the attaching and feeding member and operated in timed relation to the feeding movements thereof to vary the position of the edge gage laterally of the support thereby to vary the point of application of the strip relative to the edge of the insole, and means for controlling the operation of said edge gage operating means in accordance with differences in the sizes of insoles to be operated upon independently of the feeding movements of the strip attaching and feeding member.

8. In a machine for adhesively attaching ribbed strips to insoles, a support for an insole, means for moving the support heightwise to permit placing an insole thereon, means for adjusting the heightwise position of the support in accordance with different thicknesses of insoles, a member operated to attach the strip to the marginal portion of the insole and feed the combined insole and attached strip, power driven means for imparting to said member movement in an orbital path with components of movement heightwise relatively to the support to press the strip against the insole and transversely of the support to feed the insole, an edge gage located on the support for engagement with the edge face of the insole and movable endwise relatively to the support and heightwise with the support, and means operated by said power driven means in timed relation to the feeding movement of said attaching and feeding member to impart endwise movement to the edge gage to cause it to vary the position of the insole laterally of the support at predetermined times during an attaching cycle so as to vary the location of the strip relative to the edge of the insole along different portions thereof.

9. In a machine for attaching to an insole a strip having a rib portion and oppositely extending attaching flanges, a support for the insole, a member for attaching the strip to the insole margin and feeding the combined insole and attached strip, power driven means for imparting to the member movement in an orbital path with components of movement in one direction to attach the strip and in another direction to feed the insole, means connected to said member and operated intermittently in timed relation to the feeding movements thereof to feed the strip toward the insole, an edge gage engageable with the edge face of the supported insole to guide the insole during an attaching cycle, a cam rotated to move the edge gage laterally of the insole support to shift the insole at predetermined times during an attaching cycle to vary the location of the strip with relation to the insole edge, a connection between the cam and the pressing and feed member whereby the cam is rotated in timed relation to the feeding movements of the member, and adjustable means in said connection for variably determining the speed of rotation of the cam in accordance with the size of the insole operated upon.

10. In a machine for attaching a strip to an insole, the combination of a support for the insole, a member for attaching the strip and feeding the insole and the attached strip, power driven means for imparting to the member movement in an orbital path with components of movement in one direction to attach the strip and in another direction to feed the insole, operator controlled means for varying the length of the feeding movement of said member at will to vary the rate of feed of the insole, an edge gage engageable with the edge face of the insole to guide the insole during an attaching cycle,

a cam rotated to move the edge gage laterally of the support in accordance with a predetermined cycle to vary the position of the insole relative to the pressing and feed member so as to vary the location of the strip with relation to the insole edge, a connection between said cam and the pressing and feed member whereby the cam is rotated intermittently in timed relation to the feeding movements of said member, and adjustable means in said connection for variably determining the speed of rotation of the cam in accordance with the size of the insole operated upon independently of the rate of feed of the insole by the pressing and feed member.

11. In a machine for attaching a strip to an insole, a support for the insole, a member for attaching the strip and feeding the insole and the attached strip, power driven means for imparting to the member movement in an orbital path with components of movement in one direction to attach the strip and in another direction to feed the insole, operator controlled means for varying the length of the feeding movement of said member at will to vary the rate of feed of the insole, an edge gage engageable with the edge face of the insole to guide the insole during an attaching cycle, a cam rotated to move the edge gage laterally of the support in accordance with a predetermined cycle to vary the position of the insole relative to the pressing and feed member so as to vary the location of the strip with relation to the insole edge, a connection between said cam and the pressing and feed member whereby the cam is rotated intermittently in timed relation to the feeding movements of said member, adjustable means in said connection for variably determining the speed of rotation of the cam in accordance with the size of the insole operated upon independently of the rate of feed of the insole by the pressing and feed member, and means providing a lost motion in said adjustable means whereby the rate of feed of the insole may be varied within the limits permitted by the lost motion without varying the speed of rotation of the cam selected for a given insole size.

12. In a machine for adhesively attaching a strip to an insole, a support for the insole, a foot for pressing the strip against the insole margin and for feeding the insole and attached strip, power driven means for operating the foot, an edge gage engageable with the edge face of the insole to guide the insole during an attaching operation, a cam rotated by the power driven means to move the edge gage in a direction to vary the position of the insole widthwise of the support during an attaching cycle so as to vary the location of the strip relative to the insole edge, an adjustable limiting member, a dial having thereon indicia corresponding to insole sizes and mounted on said limiting member for adjusting the member in different positions according to the sizes of insoles to be operated upon in the machine, means connecting the cam to the pressing and feed foot to cause the cam to be rotated in timed relation to the feeding movements of the foot, operator controlled means movable between an inoperative position and different operative positions to cause the power driven means to impart to the foot feeding movements of variable length, and means between said connecting means and the operator controlled means movable with the latter to different positions determined by adjustment of the limiting member for a selected insole size to cause the cam to be rotated at a predetermined speed in accordance with the size of the insole.

13. In a machine for adhesively attaching a strip to an insole, a support for the insole, a foot for pressing the strip against the insole margin and for feeding the insole and attached strip, power driven means for operating the foot in an orbital path including a first eccentric for imparting to the foot components of movement in one direction to press the strip and a second eccentric for imparting to the foot components of movement in another direction to feed the insole, a toggle associated with each eccentric for transmitting movement from the eccen-

tric to the foot, single operator-controlled means for moving one of said toggles from its normal straightened position to a broken position to transmit to the foot uniform pressing movement and for moving the other of said toggles a variable distance from its straightened position to transmit to the foot variable feeding movement, an edge gage engageable with the edge face of the insole to guide the insole during an attaching operation, a cam rotated by the power driven means to move the edge gage in a direction to vary the position of the insole widthwise of the support during an attaching cycle, an adjustable limiting member, a dial having thereon indicia corresponding to insole sizes and mounted on said limiting member for adjusting it in selected positions according to the sizes of insoles to be operated upon in the machine, and means connecting the cam to the pressing and feed foot and to the toggle associated with the eccentric which transmits to the foot uniform pressing movement, said means being moved by movement of said toggle to its operative position to a position determined by adjustment of the limiting member for a selected insole size to cause the cam to be rotated at a predetermined speed in accordance with the insole size independently of the variable feeding movement imparted to the foot through the toggle associated with the other of said eccentrics.

14. In a machine for adhesively attaching a strip to an insole, a support for the insole, a foot for pressing the strip against the insole margin and for feeding the insole and attached strip, power driven means for operating the foot in an orbital path including a first eccentric for imparting to the foot vertical components of movement to press the strip and a second eccentric for imparting to the foot horizontal components of movement to feed the insole, a toggle associated with each eccentric and with the foot for transmitting movement from the eccentric to the foot, single operator controlled means for moving a link of one of said toggles to a predetermined angular position relative to the other link to cause the eccentric associated with that toggle to impart to the foot uniform pressing movement and for moving a link of the other of said toggles to different angular positions relative to the other link to cause the eccentric associated with that toggle to impart to the foot feeding movements of variable length, an edge gage engageable with the edge face of the insole to guide the insole during an attaching operation, a cam operated to move the edge gage in a direction to vary the position of the insole laterally of the support during an attaching cycle, adjustable limiting means movable to different positions according to the sizes of insoles to be operated upon in the machine, means connecting the cam to the pressing and feed foot whereby the cam is rotated intermittently in timed relation to the feeding movement of the foot, and a set of links between said connecting means and the toggle associated with the first eccentric which imparts pressing movements to the foot, said set of links being moved to an angular position determined by adjustment of the limiting means for a selected insole size to cause the cam to be rotated at a predetermined speed in accordance with the insole size independently of the variable feeding movements transmitted to the foot through the toggle associated with the second eccentric.

15. In a machine for attaching a strip to an insole, a support for the insole, a member for attaching the strip to the insole margin and feeding the combined insole and attached strip, power driven means for imparting to the member movement in an orbital path with components of movement in one direction to attach the strip and in another direction to feed the insole, means connected to said member and operated intermittently in timed relation to the feeding movements thereof to feed the strip toward the insole, an edge gage engageable with the edge face of the supported insole to guide the insole during an attaching cycle, a cam rotated to move the edge gage laterally of the insole support at predetermined

times during an attaching cycle to vary the position of the insole relative to the strip attaching member and thereby vary the location of the strip with relation to the insole edge, means connecting said cam to the pressing and feed member for rotation in timed relation to the feeding movements thereof, and means for selectively connecting the cam to said member for rotation in one direction when the member is to operate on insoles for the right foot and in the opposite direction when it is to operate on insoles for the left foot.

16. In a machine for adhesively attaching to an uncoated insole a strip having a rib portion and uncoated oppositely extending attaching flanges, a support for the insole, a foot for pressing the strip against the insole margin to cause it to be bonded thereto and for feeding the combined insole and attached strip, power driven means for imparting to the foot movement in an orbital path with components of movement in one direction to press the strip against the insole and in another direction to feed the insole and attached strip, means for supporting a supply of ribbed strip material, means operated intermittently by the power driven means in timed relation to the feeding movements of the pressing and feed foot to feed successive portions of strip material into engagement with the insole, strip guiding means including a nozzle along which the strip is moved toward the insole, means for holding a supply of adhesive for coating the strip flanges as the strip is moved along said nozzle, means operated intermittently by the power driven means in timed relation to the feeding movements of the foot to feed adhesive from the source of supply to the nozzle and to cause adhesive to be extruded through openings therein to coat the insole engaging surfaces of the strip flanges, manually controlled means movable from a neutral position to a fully operative position in which it renders the power driven means effective to impart feeding movement to the pressing and feed foot and drive the adhesive feeding means, and means actuated by initial movement of the manually controlled means from its neutral position to cause the adhesive feeding means to supply adhesive to the nozzle before the power driven means is rendered effective to impart feeding movement to the pressing and feed foot.

17. In a machine for adhesively attaching to an insole a strip having a rib portion and oppositely extending attaching flanges, the combination of a support for the insole, a foot for pressing the strip against the insole margin to cause it to be bonded thereto and for feeding the combined insole and attached strip, power driven means for imparting to the foot movement in an orbital path with components of movement in one direction to press the strip against the insole and in another direction to feed the insole and attached strip, means for supporting a supply of ribbed strip material, means operated intermittently by the power driven means in timed relation to the feeding movements of the pressing and feed foot to feed successive portions of strip material into engagement with the insole, strip guiding means including a nozzle along which the strip is moved toward the insole, means for holding a supply of adhesive, means operated intermittently by the power driven means in timed relation to the feeding movements of the foot to cause adhesive to be directed from the source of supply to the nozzle and extruded through openings therein to coat the insole engaging surfaces of the strip flanges, a valve movable between an initial closed position and an open position to admit adhesive to the nozzle, manually controlled means movable from a neutral position to a fully operative position in which it renders the power driven means effective to impart feeding movement to the pressing and feed foot and to drive the adhesive feeding means, means actuated by initial movement of the manually controlled means from its neutral position to cause adhesive to be supplied to said nozzle before the manually controlled means reaches its fully operative position to

render the power driven means effective to drive the adhesive feeding means, and means actuated by movement of said manually controlled means to its fully operative position to move the valve to its open position.

- 5 18. In a machine for adhesively attaching to an insole
a strip having a rib portion and oppositely extending at-
taching flanges, the combination of a support for the
insole, a foot for pressing the strip against the insole
margin to bond it thereto and for feeding the combined
10 insole and attached strip, power driven means for im-
parting to the foot movement in an orbital path with
components of movement in one direction to press the
strip against the insole and in another direction to feed
the insole and attached strip, means for supporting a
15 supply of ribbed strip material, means operated inter-
mittently by the power driven means in timed relation to
the feeding movements of the pressing and feed foot to
feed successive portions of strip material into engage-
ment with the insole, strip guiding means including a
20 nozzle along which the strip is moved toward the insole,
means for holding a supply of adhesive, means operated inter-
mittently by the power driven means in timed relation to
the feeding movements of the foot to feed adhesive
from the source of supply to the nozzle and to cause ad-
hesive to be extruded through openings therein to coat
25 the insole engaging surfaces of the strip flanges, a valve
movable between an initial closed position and an open
position to admit adhesive to the nozzle, manually con-
trolled means movable from a neutral position to a fully
30 operative position in which it renders the power driven
means operative to impart feeding movement to the press-
ing and feed foot and to operate the adhesive feeding
means, a solenoid connected to said valve, and switch
means responsive to movement of the manually controlled
35 means to its fully operative position to energize said
solenoid to move said valve to its open position.

19. In a machine for adhesively attaching to an insole
a strip having a rib portion and oppositely extending at-
taching flanges, the combination of a support for the
40 insole, a foot for pressing the strip against the insole
margin to cause it to be bonded thereto and for feeding
the combined insole and attached strip, power driven
means for imparting to the foot movement in an orbital
path with components of movement in one direction to
45 press the strip against the insole and in another direction
to feed the insole and attached strip, means for supporting
a supply of ribbed strip material, means operated inter-
mittently by the power driven means in timed relation to
the feeding movements of the pressing and feed foot to
50 feed successive portions of strip material into engagement
with the insole, strip guiding means including a nozzle
along which the strip is moved toward the insole, means
for holding a supply of adhesive, means operated inter-
mittently by the power driven means in timed relation
55 to the feeding movements of the foot to feed adhesive
from the source of supply to the nozzle and to cause ad-
hesive to be extruded through openings therein to coat
the insole engaging surfaces of the strip flanges, means
normally maintaining said strip feeding means in a pos-
60ition spaced from said nozzle, manually controlled means
movable from a neutral position to a fully operative pos-
ition in which it is effective to render the power driven
means operative to impart feeding movement to the press-
ing and feed foot and to operate the strip feeding means
65 and the adhesive feeding means, a solenoid connected
to the strip feeding means, and switch means responsive
to movement of the manually controlled means to its
fully operative position to energize said solenoid to cause
the strip feeding means to be moved toward the nozzle.

70 20. In a machine for adhesively attaching to an insole
a strip having a rib portion and oppositely extending at-
taching flanges, the combination of a support for the
insole, a foot for pressing the strip against the insole
margin to cause it to be bonded thereto and for feeding
75 the combined insole and attached strip, power driven

means for imparting to the foot movement in an orbital path with components of movement in one direction to press the strip against the insole and in another direction to feed the insole and attached strip, means for supporting a supply of ribbed strip material, means operated intermittently by the power driven means in timed relation to the feeding movements of the pressing and feed foot to feed successive portions of strip material into engagement with the insole, strip guiding means including a nozzle along which the strip is moved toward the insole, means for holding a supply of adhesive, means operated intermittently by the power driven means in timed relation to the feeding movements of the foot to feed adhesive from the source of supply to the nozzle and to cause it to be extruded through openings therein to coat the insole engaging surfaces of the strip flanges, means normally maintaining said strip feeding means in a position spaced from the nozzle, a valve movable from an initial closed position to an operative open position to admit adhesive to said nozzle, manually controlled means movable from a neutral position to a fully operative position in which it renders the power means effective to operate the pressing and feed foot, the strip feeding means and the adhesive feeding means, a solenoid connected to said strip feeding means, a second solenoid connected to said valve, and a normally open switch connected in circuit to both solenoids and closed by movement of the manually controlled means to its fully operative position to energize said solenoids simultaneously to move the strip feeding means toward the nozzle and to move the valve to its open position.

21. In a machine for adhesively attaching ribbed strips to insoles, a support for an insole, means for feeding a strip of indefinite length toward the insole, a member moved intermittently toward and away from the work to press successive portions of the strip against the insole margin to cause it to be bonded thereto and to feed the combined insole and strip, and a holdown pivotally connected to said member and actuated thereby alternately to move into engagement with the work when said pressing and feeding member is moved away therefrom after each pressing and feeding movement and to move out of engagement with the work when the pressing and feeding member is again moved toward the work.

22. In a machine for adhesively attaching ribbed strips to insoles, a support for an insole, means for feeding a strip for indefinite length toward engagement with the insole, a member operated to press successive portions of the strip against the insole margin to cause it to be bonded thereto and to feed the insole and attached strip, power driven means for imparting to said member intermittent movement toward and away from the work, starting means for rendering the power driven means operative, a holdown pivotally connected to said pressing and feeding member and operated alternately therewith to move into engagement with the work to maintain it against the support when the pressing and feeding member is moved away from the work and to move out of engagement therewith when the pressing and feeding member is moved into engagement with the work, latching means normally maintaining the holdown in an inoperative position removed from the insole support, and means actuated by operation of the starting means to cause the latching means to release the holdown for alternating movement with the pressing and feeding member at the beginning of an attaching cycle of the machine.

23. In a machine for adhesively attaching ribbed strips to insoles, a support for an insole, means for feeding a strip of indefinite length toward engagement with the insole, a member operated to press successive portions of the strip against the insole margin to cause it to be bonded thereto and to feed the insole and attached strip, positioning means normally located adjacent to the insole support and engageable with the heel end of an

70

insole to position the insole initially with relation to the pressing and feeding member for determining the starting point of attachment of the strip, power driven means for imparting to said member intermittent movement toward and away from the work, starting means for rendering the power driven means effective to operate said member, a holdown connected to said pressing and feeding member and operated alternately therewith to move into engagement with the work to maintain it against the support when the pressing and feeding member is moved away from the work and to move out of engagement therewith when the member is moved into engagement with the work, latching means normally maintaining the holdown in an inoperative position away from the work support while the machine is at rest, and means actuated by operation of said starting means to move said positioning means out of engagement with the insole and to cause the latching means to release the holdown at the beginning of an attaching cycle of the machine.

24. In a machine for attaching a ribbed strip to an insole to provide a sewing rib thereon, a support for the insole, means for directing a strip toward the insole, means for progressively attaching the strip to the margin of the insole at variable distances from the edge thereof and for feeding the insole over the support, an edge gage associated with the support for controlling the position of the insole laterally of the support and of the point of application of the strip relative thereto, power operated means for moving said edge gage laterally of the support in accordance with a predetermined cycle to vary the position of the insole on the support relative to the strip attaching means during an attaching operation, and means operated by said edge gage moving means at a predetermined time in an attaching cycle to stop the operation of the attaching and feeding means.

25. In a machine for adhesively attaching a strip to an insole, a support for the insole, a foot for pressing the strip against the insole margin to cause it to be bonded thereto and for feeding the combined insole and attached strip, power driven means for imparting to the foot movement in an orbital path with components of movement in one direction to press the strip and in another direction to feed the insole and attached strip, a treadle, means operated by the treadle to render the power driven means effective to operate the foot, a connection between the treadle and the means operated thereby comprising a pivoted arm, a rod connecting said arm to the treadle operated means, a latch member, a rod connecting said latch member to the treadle, a lever connected to said arm and engaged by said latch member to connect the treadle to the treadle operated means, a solenoid connected to said lever, an edge gage engageable with the edge face of the insole on the support to guide the insole during an attaching cycle, a cam for moving the edge gage at predetermined times during a strip attaching cycle to vary the position of the insole laterally of the support so as to vary the location of the strip along the insole margin, means connecting said cam to the power driven means and to the foot and operated to cause the cam to be rotated at a speed such that it will complete a revolution substantially at the time when the attaching operation reaches a point on the insole opposite the starting point, and switch means actuated by said cam upon completion of a revolution thereof to energize said solenoid and cause it to break the connection between the treadle and the treadle operated means, thereby to stop the operation of the pressing and feed foot.

26. In a machine for attaching a ribbed strip to an insole to provide a sewing rib thereon, a support for the insole, means for directing a strip toward the insole, means for progressively attaching the strip to the margin of the insole at variable distances from the edge thereof and for feeding the insole over the support, power driven

means movable from an inoperative position to a position in which it renders said attaching and feeding means operative, an edge gage associated with the support for controlling the position of the insole laterally of the support and of the point of application of the strip relative thereto, means operated by said power driven means for moving said edge gage laterally of the support in accordance with a predetermined cycle to vary the position of the insole on the support relative to the strip attaching means during an attaching operation, means operated by said edge gage moving means at a predetermined time in an attaching cycle to cause movement of the power driven means to its inoperative position thereby to stop the operation of the attaching and feeding means, means for severing the strip at the end of an attaching operation, and means rendered operative upon movement of said power driven means to its inoperative position to operate the strip severing means.

27. In a machine for adhesively attaching a strip to an insole, a support for the insole, a foot for pressing the strip against the insole margin to cause it to be bonded thereto and for feeding the combined insole and attached strip, power driven means for imparting to the foot movement in an orbital path with components of movement in one direction to press the strip and in another direction to feed the insole and attached strip, a treadle, means operated by the treadle to render the power driven means effective to operate the foot, means connecting the treadle and the means operated thereby, an edge gage engageable with the edge face of the insole to control the position thereof relative to the pressing and feed foot, a cam for moving the edge gage at predetermined times during an attaching cycle to vary the position of the insole laterally of the support and thereby vary the point of application of the strip relative to the edge of the insole, means connecting said cam to the power driven means for rotating the cam in timed relation to the feeding movements of the foot, means actuated by said cam for moving the means connecting the treadle to the treadle operated means in a direction to break the connection between them so as to stop the operation of the pressing and feed foot as the cam completes a revolution, a knife for severing the strip at the completion of an attaching operation, a solenoid for operating the knife, switch means closed by movement of said connecting means to

45

their broken position for energizing said solenoid to operate the severing knife.

28. In a machine for adhesively attaching a strip to an insole, a support for the insole, a foot for pressing the strip against the insole margin to cause it to be bonded thereto and for feeding the combined insole and attached strip, power driven means for imparting to the foot movement in an orbital path with components of movement in one direction to press the strip and in another direction to feed the insole and attached strip, a treadle, means operated by the treadle to render the power driven means effective to operate the foot, means connecting the treadle and the means operated thereby, an edge gage engageable with the edge face of the supported insole to control the position of the insole relative to the pressing and feed foot, a cam for moving the edge gage at predetermined times during an attaching cycle to vary the position of the insole laterally of the support and thereby vary the point of application of the strip relative to the edge of the insole, means connecting said cam to the power driven means for rotating the cam in timed relation to the feeding movements of the foot, means actuated by said cam for moving the means connecting the treadle to the treadle operated means in a direction to break the connection between them so as to stop the operation of the pressing and feed foot as the cam completes a revolution, a knife for severing the strip at the completion of an attaching operation, a solenoid for operating the knife, switch means closed by movement of said connecting means to their broken position for energizing said solenoid to operate the severing knife, and switch means actuated by the knife as it completes its operative stroke to deenergize said solenoid so as to permit the knife to be returned to its inoperative position and to cause the treadle to be reconnected to the means operated thereby for a subsequent operation.
